UNITED STATES PATENT OFFICE.

STANLEY W. HAYES, OF GENEVA, NEW YORK.

DERAILER.

No. 843,455.

Specification of Letters Patent.

Patented Feb. 5, 1907.

Application filed August 16, 1906. Serial No. 330,786.

To all whom it may concern:

Be it known that I, STANLEY W. HAYES, a citizen of the United States, and a resident of Geneva, in the county of Ontario and State 5 of New York, have invented certain new and useful Improvements in Derailers, of which the following is a full and concise specification.

My invention relates to derailers, and 10 more especially to a means of mounting and guiding the movable wheel-derailing member thereof upon the base member, whereby the reciprocation of the derailing member by a suitable connection at its rear end will cause 15 a lifting or up-and-over movement of the rail-block at the other end.

The invention also involves the relative 20 arrangement of the parts for effecting the above motion and the arrangement of the locking means, all as will be fully described and herein claimed.

In the accompanying drawings, forming a part hereof, Figure 1 is a plan view of a derailler, with the derailing member in an intermediate or half-way position, constructed 25 in accordance with my invention and with half of the base member thereof broken away. Fig. 2 is a vertical transverse section of Fig. 1 on line II II. Figs. 3 and 4 are side 30 elevations with base in section and derailing member respectively in closed and open positions. Fig. 5 is a rear elevation with a central operating or locking connection. Fig. 6 is a detail in section of said central connection, and Fig. 7 is a side elevation of the device of Fig. 5 with the central connection 35 reversed.

The base member of the device above illustrated is comprised of a single casting, 40 which is formed with two side walls 11, base-flanges 22, suitably reinforced by integral angle-braces 2', and a cross-piece 3, joining the two walls at the top. On the under sides of the base-flanges are two parallel tie-flanges 44, which are adapted to engage and space the edges of two adjacent ties when the member is installed on the road-bed so as to anchor the apparatus firmly thereto. The forward portion of the base is slightly 45 elevated and extends above the base-flange of the rail, forming a seat or pocket 5, which is adapted to receive a corresponding part of the derailing member when it is in its operative or active position to sustain it against 50 movement parallel with the rail. The por-

tion of the base member in the rear of the cross-piece 3 is formed as a slideway.

The wheel-derailing member comprises a derail-block 6 of ordinary formation, carried by a derail-block arm 7, which is mounted to 60 reciprocate within the chamber formed by the walls of the base member. At its forward or derail-block end the arm 7 is carried by a rocking link 8, which is pivoted to the base by means of the cross-pin 9, the latter 65 being supported in the base by the tie-flanges or by the lugs 10, which constitute parts of said flanges. The upper end of the link occupies a straight-sided groove or recess formed in the under side of the derail-block arm and 70 is pivoted thereto by means of the pin 11, secured in the side walls of the arm. The rear end of the derail-block arm is adapted to slide in the rear portion of the base in a substantially straight direction toward and from the 75 rail, and to this end it is provided with lateral lugs 12, which rest on the inwardly-projecting flanges 13 of the base, the latter forming the slideway. However, the lugs can be formed on the base to engage grooves in the sides of 80 the arms with equal effect. The lugs are round, so as to permit the lifting movement of the derail-block. The means whereby the above device may be operated and also locked in position (in interlocking plants) are applied directly to the derailing member at the extremity of the arm 7 and comprise two connection-lugs 15 and 15', which are formed as integral extensions of the side walls of the arms and depend therefrom to a point below 85 the lugs and slideway, and preferably below the level of the cross-pin 9. One or both of these lugs may be used, as desired. The operating-jaw 14 is pivoted to the end of the lug by a pin or bolt. When one of the lugs is 90 thus employed for operating, the other may be employed for the locking means, and a second connection means, presently to be described, may also be employed. In Figs. 6 and 7 the lug 15' is connected with a flat bar 100 17, which is a part of an ordinary facing-point lock not requiring description. When the derailing member is moved to either position, this device serves to lock it in place in well-understood manner. The second locking means, or it may be a signal-operating means or a secondary operating means, is intended to be connected directly to the derailing member by being pinned to the connection-head 18 of a bolt 19, which is set into the 105 110

cross-flanges 7' of arm 7, occupying a central position with respect to the lugs 15 and 15' and being also somewhat below the slideway, Figs. 5 and 6. This bolt is reversible, so that the perforated connection-head 18 can be placed under the arm 7, where it can be more conveniently operated by a connection coming from an opposite direction, as clearly indicated in Fig. 7. One or more of these connections may be employed, according to requirements.

The link 8 is so pivoted with respect to the horizontal traverse of the derailing member that when the latter is withdrawn from the rail it occupies the inclined position, not quite horizontal, which is indicated in Fig. 3, the derail-block in this position being depressed; but when the derailing member is pushed forward by the operating connection above mentioned the direction of the operating force is such that the link is lifted by the pressure on the arm and rocked forward to the inclined position shown by Fig. 4. In swinging forward the link imparts a rising or up-and-over movement to the derail-block, which movement serves to place it properly upon the rail. The action is of course the reverse in withdrawal. The link is of massive proportions relative to the rest of the apparatus and fits rather snugly within the recess of the arm, so that it is specially suited to guide and steady the derail-block during its movement and also to aid in resisting the severe strains of derailing, and in swinging over its point of unstable equilibrium it lends its own considerable weight to that of the other moving parts, so that the derailing member is carried with a free and easy swing to the extreme end of its traverse in either direction—that is to say, the center of gravity of the heavy link is mounted so that it must pass over its point of pivotal support, and therefore requires only to be lifted during the beginning of the stroke to its point of unstable equilibrium, whereupon it moves by gravity the rest of the stroke, and thereby effects a full and complete "throw" with the minimum of exertion, it being a most desirable point in track appliances of this kind that the moving parts are readily and freely moved, especially during the latter part of their strokes.

In its closed position the derail-block rests upon the side walls of the base and in this position maintains the link in the inclined position shown in Fig. 3, keeping it from dropping below dead-center. By attaching the operating connection 14 to the end of the connection-lug, which thus becomes a crank-arm, the force applied in pushing the derailing member toward the rail becomes resolved partly into a rotary force, which tends to turn the derail-block arm on the lugs 12 as a center, and therefore helps in raising and throwing the link forward over its pivot-pin

9, all of which is important in facilitating the action of the mechanism, as is plain to those skilled in the art.

In order that the derail-block may assume its depressed position resting on the walls of the base, recesses 16 are formed in its sides to accommodate the cross-pin 9, as indicated in the drawings.

Having described my invention, what I claim, and desire to secure by United States Letters Patent, is—

1. In a derailer, a wheel-derailing member, a rocking link supporting the derail-block end of said member and adapted to impart a lifting movement thereto, means for slidely supporting the other end of said member and an operating connection attached directly to said derailing member.

2. In a derailer, a wheel-derailing member, a base member therefor, a link supported by said base member and adapted to swing over its point of support, the derail-block end of said derailing member being pivotally carried by the upper end of said link, in combination with a slideway formed in the rear of said base member and an operating connection attached to the rear end of said derailing member and adapted to force the said member and link toward the rail.

3. In a derailer, a wheel-derailing member, a rocking link supporting the derail-block end of said member and adapted to impart an up-and-over movement thereto, in combination with means for slidely supporting the rear end of said member, and a connection-lug extending downwardly from the rear portion of said member, adapted to be engaged by the means for operating the derailer.

4. In a derailer, a wheel-derailing member, a rocking link supporting the derail-block end thereof, a base to which said link is pivoted, means on the base for slidely supporting the other end of said member, and a connection-lug formed on the rear end of said derailing member and extending downwardly below the level of the said means.

5. In a derailer, a wheel-derailing member, a link supporting the derail-block end thereof, and means for slidely supporting the other or rear end thereof, in combination with a base, a cross-pin carried thereby supporting said link, and an operating means connected to said rear end of the member, adapted to operate below the level of said cross-pin.

6. In a derailer, a wheel-derailing member having a recess in its under side, a rocking link having its upper end within said recess and a cross-pin held in perforations in the sides of said member and passing through said link, the said link being of sufficient width to fit snugly in said recess, in combination with a base member provided with means for slidely supporting the rear end of the derailing member.

7. In a derailer, a base member having base-flanges adapted to rest on the ties, tie-flanges on the under side of said base-flanges farther apart than the width of the base member and adapted to space the ties, and a cross-pin carried by said tie-flanges, in combination with a link pivoted to swing over said cross-pin, a wheel-derailing member carried by said link and means for moving the same and said link toward and from the rail.

8. In a derailer, a wheel-derailing member, a base member formed of side walls, base-flanges adapted to rest on the ties, and a cross-piece joining said side walls at the top, in combination with a rocking link pivotally carried by the front portion of said base and adapted to support and impart a lifting movement to said derailing member, a slide-way formed in said base member in the rear of said cross-piece, and a connection means on the rear of said derailing member.

9. In a derailer, a wheel-derailing member, a rocking link supporting the derail-block end thereof and adapted to impart a lifting movement thereto, means for slidely supporting the other end of said member and a locking connection for the device applied directly to the said derailing member.

10. In a derailer, a wheel-derailing member, means for imparting an up-and-over movement to one end thereof and a slideway supporting the other end, in combination with a cross-flange on said derailing member and a bolt having a connection-head, reversibly secured in said cross-flange.

In testimony whereof I have signed my name to the specification in the presence of two subscribing witnesses.

STANLEY W. HAYES.
